Patented Feb. 8, 1972

222,931

DISPENSING CONTAINER FOR LIQUIDS OR THE LIKE

Louis V. Nigro, Saugus, Mass., assignor to The Gillette
Company, Boston, Mass.

Filed Oct. 26, 1970, Ser. No. 25,634

Term of patent 14 years

Int. Cl. D9—01

U.S. Cl. D9—83

Fig. 1

Fig. 2

Fig. 3

Fig. 4

Fig. 5

Fig. 6

FIG. 1 is a perspective view of a dispensing container for liquids or the like showing my new design;

FIG. 2 is a top plan view thereof;

FIG. 3 is a right side elevational view thereof;

FIG. 4 is a back elevational view thereof;

FIG. 5 is a front elevational view thereof; and

FIG. 6 is a bottom plan view thereof.

The undisclosed side is substantially a mirror image of the side shown.

I claim:

The ornamental design for a dispensing container for liquids or the like, substantially as shown and described.
